UNITED STATES PATENT OFFICE.

STEPHEN P. SANDERS, OF CUPERTINO, CALIFORNIA.

CARBURETER.

1,152,915.

Specification of Letters Patent. Patented Sept. 7, 1915.

Application filed October 28, 1914. Serial No. 868,922.

To all whom it may concern:

Be it known that I, STEPHEN P. SANDERS, a citizen of the United States, residing at Cupertino, in the county of Santa Clara and 5 State of California, have invented new and useful Improvements in Carbureters, of which the following is a specification.

This invention relates to a carbureter especially constructed for volatilizing low-grade hydrocarbon fuels and mixing same with air to produce a gas suitable for household uses, such as lighting and cooking.

One of the objects of the invention is to provide a simple, cheaply manufactured, 15 easily operated carbureter which is compact in construction and automatic in operation and which is provided with means for automatically admitting air and gasoline to the carbureting chamber in measured quantities.

20 Another object of the invention is to provide an auxiliary vaporizing attachment, by means of which the fuel may be further volatilized and a perfect mixture secured. Further objects will hereinafter appear.

25 The invention consists of the parts and the construction and combination of parts as hereinafter more fully described and claimed, having reference to the accompanying drawings, in which—

30 Figure 1 is a side elevation of the carbureter and gasometer, with connected operating mechanism. Fig. 2 is a vertical central section of the carbureter. Fig. 3 is a perspective of one of the fiber cartridges mounted in the carbureting tube. Fig. 4 is a cross section on line 4—4, Fig. 5, with fiber in place. Fig. 5 is a side elevation of the fiber cartridge frame employed in the auxiliary vaporizer.

40 More particularly described, A indicates the carbureter proper, B a receiver or gasometer connected with same, and C the coils of an auxiliary vaporizer hereinafter to be more fully described. The carbureter proper consists of a double walled tank A, in the 45 annular space of which is vertically movable a bell 2, said annular space being filled with water or any other suitable liquid to form a seal for the bell.

50 Centrally mounted in the inside tank is a cylinder 3 and movable in said cylinder is a piston 4 with which bell 2 is connected by means of a rod 5. Extending outwardly from the rod in a horizontal position is an 55 arm 6, and depending from said arm, by a

link 7, is a bucket 8. This bucket is pivoted off center, as at 9, so that it will normally assume the tilted position shown in Fig. 2, which position is limited by a set-screw 10. The inner tank may be filled with gasoline, 60 as indicated at 11, through a screw plug opening 12 formed in the bell or by means of a floating valve or any other suitable connection. The quantity of gasoline contained or elevated by the bucket, when the bell 65 moves in an upward direction, is regulated by the tilted position of same or the adjustment of set-screw 10.

Secured inside of the inner tank and mounted eccentrically with relation to cylinder 3 is a second cylinder 13 which will hereinafter be termed the "carbureting tube." This tube is provided with an inclined extension tube 14 through which the gasoline, 70 elevated by bucket 8, is delivered to the carbureting tube proper. The carbureting tube is open at its upper end and communication therewith is also formed through the filling tube 14.

75 Mounted interiorly of the tube below the filling opening is a plurality of fiber cartridges 15 which are stacked one upon the other. These cartridges are more particularly shown in Fig. 3 and consist of a wire screen ring 16 over which is wound, lengthwise and crosswise, a cotton or hemp string, such as is indicated at 17. This in a manner forms a coarse fabric on both sides of the ring through which the gasoline admitted through tube 14 is permitted to 80 pass. A portion of the gasoline poured in through the filling tube becomes absorbed by the fiber strings of the several cartridges as a great number of same are stacked one 85 upon the other throughout the length of the tube.

90 The piston 4, with connected bell 2, is preferably lifted by water under pressure entering through a pipe 18 connected with a suitable source of supply. The water admitted through pipe 18 to lift piston 4 is controlled by a pair of valves 19 and 20; valve 19 being the inlet valve and valve 20 being the exhaust or outlet valve. These valves are automatically opened and closed, 95 as the case may be, by a tappet head 21, pivotally mounted, as at 22, upon a standard 100 23. This in turn is operated by a cross-arm or tube 24 which is connected by a chain 25 with an arm 26 secured to the bell on one 105 110

side and by a cable 27 passing over a pulley 28 on the other side.

In operation, when the bell moves down to the extreme lower position, cable 27 will be pulled in the direction of arrow *a* and will consequently tilt tube 24, with connected tappet head 21 about pivot 22. This will bring shoulder 29 of the tappet head in engagement with a lever 30 on the exhaust valve and will depress this or move it into the closed position. The lower shoulder 31 on the tappet head will at the same time engage the other side of a similar lever 32, with which valve 19 is connected, and move this to the open position. The water through pipe 18 will thus be directed upwardly into the cylinder and will consequently lift the piston with connected bell. The upward movement of the bell will elevate bucket 8 into registering position with the filling tube 14 where the spout of the bucket engages with a projection 14^a formed on the filling tube causing the bucket to be tilted and the contents emptied. The moment the bell has been lifted to its extreme upward position chain 25 will reverse the movement of the tappet head, causing this to close valve 19 and open exhaust valve 20. The water previously admitted to the cylinder is thus permitted to escape and bell 2, with connected rod and piston, will consequently be permitted to drop down and expel the air previously admitted. The air passing through the fiber cartridges which have just been saturated with gasoline will become highly volatilized and will pass from the lower end of the carbureting tube into the gasometer indicated at B, or may escape through the service pipe 33 for direct use.

One of the important features of the present invention is the provision of an auxiliary vaporizer. This is interposed between the outlet of the carbureting tube 13 and the gasometer B and all the gas previously produced in the carbureting tube is further acted on by being passed through the auxiliary carbureter indicated at C. This carbureter consists of three or more tubes 34, 35 and 36, interior of which are mounted a plurality of fiber cartridges such as indicated in Figs. 4 and 5.

Mounted on the lower pipe 36 of the auxiliary carbureter is an inlet valve 37 and a check-valve 38. All air admitted to the carbureter on the upward movement of the bell enters through valve 37, then passes through the several fiber cartridges mounted in tubes 35 and 34 and the cartridges mounted in the carbureting tube 13. The air is thus partly volatilized on the suction or intake stroke of the bell, but the complete volatilization takes place on the downward movement of the bell as the several fiber cartridges are thoroughly saturated with gasoline just previous to the downward movement of the bell. The air

will pass through the cartridges 15 in the carbureting tube and then through the cartridges in the tubes 34, 35 and 36 and is finally permitted to enter the gasometer B or flow directly through the service pipe 33 for distribution.

The cartridges introduced into the tubes 34, 35 and 36 are preferably cylindrical in cross section, as indicated in Fig. 4, and are constructed in lengths suitable for various installations. These tubes are constructed of wire fabric and a fibrous string, such as cotton or hemp, is then threaded through same, as indicated in Fig. 4. The gasoline coming from the carbureting tube and draining into tubes 34, 35 and 36 will thus be absorbed by the fiber of the auxiliary vaporizing cartridges. The action of capillary attraction will cause the gasoline to be completely absorbed by the fibrous strings of the several cartridges and it is here presented to the volume of moving air in the highly attenuated form where it will be quickly absorbed. Dry carbureted air is thus quickly produced by the use of a very simple apparatus which may be operated with a minimum amount of power from such sources as storage water tanks, and the like.

Tube 24 is preferably loaded with mercury so that the arm, when once moved a little beyond the horizontal in either direction, will quickly drop to one side or the other to open or close the respective valves.

The gasometer is provided with only one connection 33^a in the bottom through which the carbureted air ebbs and flows. While the bell of carbureter A is coming down, the pressure produced forces the carbureted air along to the gasometer and also to the burners on the service pipe. As soon as the bell of carbureter A reverses or moves up on its suction stroke, the pressure will cease and the burners or lights will become extinguished. This is, however, prevented by the closing of check valve 38 and the surplus supply of carbureted air carried by the gasometer. This action is instantaneous without the least fluctuation in the lights or burners. The ebb from the gasometer sets in instantly and supplies the service pipe. Weights are placed in the two bells to regulate the carbureted air pressure and to keep them in balance with each other.

A machine constructed as here shown permits the generation of carbureted air of fixed and uniform quality. Knowing the cubic contents of the carbureting bell, it is possible to adjust the cup 8 to dip and empty just the right quantity of gasoline to saturate that much air to make the carbureted air just the richness desired. When so adjusted, carbureted air of absolute uniform standard richness, independent of heat or cold, wet or dry, is secured. The richness of the carbureted air may be changed at any

time by adjusting the dip of the cup. The machine will thus generate the desired mixture continuously until again adjusted by the operator.

5 The auxiliary carbureter is an extension of the carbureting tube, and the interior of same is provided with the same fuzzy strings for the purpose of distributing, by capillary attraction, the gasolene in extremely attenuated form to the moving volume of air. All the gasolene that trickles through the carbureting tube creeps along in the trough of the auxiliary tube and climbs up the flax threads when it is swept off as vapor by the 10 passing current of air. The lower auxiliary tube is provided with a grease trap 36^a in which the greasy residue of the gasolene is collected.

15 A pet cock 36^b is provided at the bottom of the trap so as to permit the removal from time to time of the collected residue. The provision of the trap keeps the carbureter clean and also prevents the service pipe from becoming choked.

20 25 I wish it understood that various other modifications may be made within the scope of the appended claims and that I do not wish to limit myself to the specific design and construction here shown.

30 The materials and finish of the several parts of the carbureter are such as the ex-

perience and judgment of the manufacturer may dictate.

Having thus described my invention, what I claim and desire to secure by Letters Patent is—

1. In a carbureter having a carbureting chamber, a cartridge in the chamber composed of a pair of substantially parallel spaced rings connected by spaced cross rods, 40 and fabric strings stretched across the rings and across the space between the rings and rods so as to form a drum defined in outline by a network of strings.

2. In a carbureter, a cartridge composed 45 of a pair of substantially parallel spaced rings, cross rods connecting the rings and having their ends extending beyond the respective rings, and fabric strings stretched across the rings and transversely across the 50 space between the rings and around said rod ends so as to form a drum defined at its top, bottom, and periphery by a network of strings.

In testimony whereof I have hereunto set 55 my hand in the presence of two subscribing witnesses.

STEPHEN P. SANDERS.
